FLUID PRESSURE GENERATOR

Vernie E. Clarke, Los Angeles, Calif., assignor to
 Christine Association, Inc., Los Angeles,
 Calif.

Application May 10, 1937, Serial No. 141,637

5 Claims. (Cl. 219—38)

This invention relates to a fluid pressure generator and has as its primary object the provision of a means for effecting continuous vaporizing of a liquid to develop a large volume of vapor under high pressure without the employment of a boiler.

Another object is to provide a device for effecting instantaneous vaporization of water through the medium of the electrical current, and which device is so formed as to be rapid and thorough in its action and capable of generating a considerable volume of vapors under high pressure in a small space.

Another object is to provide a fluid pressure generator which is especially applicable for use in the generation of steam to be utilized in the development of mechanical power and where a large volume of steam and a continued supply thereof is required.

Another object is to provide a generator of the above character including a steam generating chamber with an electrical heating element arranged therein, together with a water feed nozzle constructed and arranged to direct a jet of water in an extremely fine stream into the chamber in a manner such that the heat developed by the heating element will effect instantaneous conversion of the water into steam, and embodying a construction whereby assembling of the heating element and the nozzle and mounting thereof on the generator will be facilitated.

A further object is to provide a generator of the above character in which the parts are so formed and assembled as to insure against pressure leaks and to enable development of extreme high pressures with safety.

With the foregoing objects in view together with such other objects and advantages as may subsequently appear, the invention is carried into effect as hereinafter described and claimed and as illustrated by way of example in the accompanying drawing in which:

Fig. 1 is a view in transverse section and elevation of the generator;

Fig. 2 is a plan view of the generator;

Fig. 3 is a detail in cross section taken on the line 3—3 of Fig. 1;

Fig. 4 is a diagrammatic view illustrating the application of the invention.

Referring to the drawing more specifically, in which corresponding reference characters indicate corresponding parts in the several views, 6 indicates a metallic cylinder which is fitted with end plates 7 and 8 to form a vapor generating chamber A interiorly of the cylinder. The plates

7 and 8 seat on the end of the cylinder 6 and are held in place thereon by a series of bolts 9 which pass through marginal portions of the end plates protruding beyond the outer periphery of the cylinder 6; the bolts having heads 10 bearing against washers 11 on the outer face of the end plate 8 and having nuts 12 screwed on their opposite ends bearing against washers 13 seating on the outer face of the end plate 7. The end plates are formed with smooth annular walls 14 and 15 which abut against the inner periphery of the cylinder to centralize the end plates on the cylinder and to hold the end plates against lateral shifting as well as to form a broken joint connection between the end plates and cylinder. 15

The end plates 7 and 8 are formed with central openings 16 and 17 in which are inserted from opposite sides of each of the plates a pair of insulating sleeves 18 and 19 between the adjacent inner ends of which is imposed an insulating packing 20 and which sleeves are formed with end flanges adapted to seat on the opposite faces of the end plates.

Extending through the sleeves 18 and 19 on the end plates 7 and 8 are electrically conductive plugs 21 and 22 formed with marginal flanges a, the inner ends of which seat on rings 23 and 24, which in turn seat on the flanged ends of the insulating sleeves 19; the rings 23 and 24 having marginal flanges b arranged to encircle the marginal flanges a on the plugs 21 and 22. Extending between the plugs 21 and 22 and carried by the flanges a thereof is a series of electrically conductive and resistant wires 25 constituting electrical heating elements; the wires 35 being here shown as connected to the plugs 21 and 22 by being passed through openings c in the base portion of the flanges a and extended outwardly along the inner faces of the flanges a thence across the peripheral faces of the flanges 40 in registering grooves d formed on the contiguous faces of the flanges a and b.

The plugs 21 and 22 are formed with exteriorly threaded end portions e which project through the insulating sleeves 18 and are engaged by 45 nuts 26 which are screwed thereon and bear against washers 27 seating on the outer faces of the insulating sleeves 18; the nuts 26 and their screw thread connections with the plugs serving in conjunction with the flanges a to clamp the insulating sleeves 18 and 19 securely against the end plates 7 and 8 and compress the insulating packing 20 between the adjacent ends of the sleeves 18 and 19 and around the shanks of the 50 55

plugs 21 and 22, and at the same time tightly clamp the conductor wires 25 between the flanges *a* and rings 24. In this fashion the plugs and the heating elements are securely fastened in place on the end plates 7 and 8 and insulated therefrom with leak-proof joints therebetween.

Connecting with the plugs 21 and 22 and leading from any suitable source of electrical current supply are electrical conductors 28 and 29 having terminals *f* which encircle the outer end portions of the plugs 21 and 22 and seat on the nuts 26, and screwed on the outer end portions of the plugs are nuts 30 which clamp the terminals *f* tightly against the nuts 26. In this fashion electrical connection from a source of electric current supply is afforded to the electrical heating element interiorly of the cylinder 6 through the electrically conductive plugs 21 and 22 extending through the end plates 7 and 8.

20 In carrying out the invention the plug 21 is hollow and is formed at its inner end with a cylindrical opening *g* leading from the interior of the plug to the chamber A interiorly of the cylinder 6. Projecting in the open out end of the plug 21 is a tube 31 having a reduced outer end portion which extends through the opening *g* and has a tapered extremity *h* protruding beyond the inner end of the plug 21 constituting a nozzle and which tapered extremity is formed with a 30 needle orifice *i* leading from the tip of the nozzle to a cylindrical bore *j* leading through the cylindrical end portion *g* and communicating with the interior of the tube 31. The outer end portion of the tube 31 is formed with an annular flange 32 which seats on the outer end of the plug 21 and is engaged by a gland 33 screwed on the plug 21 and fitted with a packing 34 to seal the joint between the tube 31 and the outer end of the plug 21.

40 Extending into the tube 31 is a conduit 35 leading from any suitable source of liquid supply under pressure; the inner end of the conduit 35 being formed with a cylindrical nozzle *k* extending into the cylindrical bore *j* and terminating contiguous the inner end of the needle orifice *i*. The conduit 35 is formed with an annular flange 36 which seats on the outer end of the tube 31 and is engaged by a gland 37 screwed on the tube 31 and engaging a packing 38 to seal the joint between the conduit 35 and the outer end of the tube 31.

50 In the application of the invention as shown in Fig. 4, the conduit 35 leads from the discharge end of a double acting pump B adapted to deliver a substantially continuous stream of liquid, such as water, to the nozzle *h* and under such pressure that the needle orifice *i* will project into the generating chamber A a jet of finely divided or atomized water, or other liquid. The generator is housed in a casing C, as shown in Fig. 4, between which and the generator is a heat insulating packing D, and leading from the generating chamber A is a vapor discharge nozzle E connecting with an opening 49 in the cylinder 6 intermediate the ends thereof which nozzle is here shown as connected to the intake of a turbine F.

60 In the operation of the invention electrical current is directed through the heating elements 25 whereby the latter, by reason of their resistance, are heated to an incandescent state, and liquid, such as water, is directed into the chamber A into the space surrounded by the heating elements through the nozzle *h* in an atomized jet; the water being so finely divided that the heat developed in the chamber A will effect substantially

instantaneous, or flash, vaporization of the minute water particles, thereby immediately converting the water into steam as it is delivered into the generating chamber A. Manifestly this rapid conversion of water into steam will develop a 5 considerable volume of steam under high pressure within the generating chamber A, which pressure will be determined by and may be varied by the rate of discharge of steam from the generator through the discharge nozzles E. 10

It will now be seen that by the use of my invention a very small quantity of water is directly acted upon by a very intense heat within a generating chamber formed to withstand extremely high pressures resulting from the expansion of water to a very large volume of super-heated steam, and that the steam so developed is not retained in the generator but its expansion quality is immediately communicated to a unit as a highly effective motivating medium. 20

While I have shown and described a specific embodiment of my invention, I do not limit myself to the exact details of construction and arrangement shown but may employ such changes and modifications as occasion may require coming 25 within the meaning and scope of the appended claims.

I claim:

1. In a vapor generator, a cylinder, end walls on said cylinder, electrically conductive plugs extending through said end walls and insulated therefrom, electrically conductive resistant wires leading between said plugs, one of said plugs being hollow, and a nozzle extending through said hollow plug having a needle orifice opening interiorly of said cylinder, means for directing liquid under pressure through said nozzle, and means for delivering generated vapors from said cylinder. 30

2. In a vapor generator, a generating chamber, 40 electrically conductive plugs extending through opposed walls of said chamber and insulated therefrom, electrically conductive and resistant wires connecting said plugs interiorly of said chamber, and a liquid feed nozzle extending into 45 said chamber through one of said plugs.

3. In a vapor generator, a generating chamber having a wall, a hollow electrically conductive plug extending through said wall and insulated therefrom, an electrical heating element in said chamber connected to said plug, a tube extending into said plug, a nozzle on said tube extending through the inner end of said plug into said chamber having a needle orifice, a liquid supply tube connecting with said nozzle, and means for 50 directing generated vapors from said chamber. 55

4. In a vapor generator, a generating chamber having a wall formed with an opening, a pair of insulating sleeves extending to said opening from opposite sides thereof and insulating packing interposed between adjacent ends of said sleeves and electrically conductive plug extending through said sleeve having end flanges overlying the innermost sleeve, a nut screwed on the outer end of said plug overlying the outermost sleeve, 60 an electric heating element connected to said plug interiorly of said chamber, and an electric conductor connecting with the other end portion of said plug. 65

5. In a vapor generator, a generating chamber having a wall formed with an opening, a pair of insulating sleeves extending to said opening from opposite sides thereof and insulating packing interposed between adjacent ends of said sleeves and electrically conductive plug ex- 70 75

tending through said sleeve having end flanges overlying the innermost sleeve, a nut screwed on the outer end of said plug overlying the outermost sleeve, an electric heating element connected to said plug interiorly of said chamber, and an electric conductor connecting with the other end portion of said plug, said plug being hollow and

5 formed with an opening in its inner end, a tube extending into said plug formed with a nozzle having a needle orifice projecting through said opening, and a liquid supply conduit connecting with said tube.
